PLANER HAVING WORK PIECE CARRYING BELT

Burke E. Porter and Alexander H. Stuart, East Grand Rapids, Mich., assignors to Porter-Stuart Company, Grand Rapids, Mich., a partnership

Application November 18, 1954, Serial No. 469,810

11 Claims. (Cl. 144—128)

This invention relates to wood working machinery and more particularly to a planer having a novel feeding mechanism for the work pieces.

Planers of conventional design use top and bottom rollers as the means for feeding the work past the cutting head. This arrangement has several disadvantages among which are the inability of such machines to handle short lengths of material and the high pressures necessary to grip and positively feed the work pieces through the machine.

This invention is designed to overcome these difficulties by providing a new and novel structure for feeding the materials past the cutter head. This invention makes it possible to successfully plane work pieces which are substantially less than a foot in length. The invention also eliminates the necessity for heavy pressure rollers, particularly those having a grooved surface. This eliminates possible indentation of the wood which may not be removed by the planer.

The invention has the added advantage of positively holding the work pieces at all times, thus reducing the danger of kickbacks in the event there is a bind with the cutter head.

The machine produced by this invention, while positively feeding even small work pieces, is of simple construction and is adapted to use in both large and small planers.

These and other advantages of this invention will be immediately seen by those acquainted with the design and use of wood working machinery upon reading the following specification and the accompanying drawings.

In the drawings:

Fig. 1 is a fragmentary side elevation view of a planer incorporating our invention.

Fig. 2 is a sectional elevation view taken along the plane II—II of Fig. 1.

Fig. 3 is an enlarged, fragmentary, plan view of a planer incorporating our invention, with the hood removed.

Fig. 4 is an enlarged, fragmentary, sectional view taken along the plane IV—IV of Fig. 2.

In executing the objects and purposes of our invention, we have provided a rubber-like belt having a high surface friction as the carrying means for transporting the work pieces through the planing operation. This endless belt is driven by suitable means and as it passes under the cutter head it is supported by a plurality of closely spaced rollers. Means are provided above the belt, on each side of the cutter head, to press the work pieces against the belt and assure their movement against the resistance of the cutting operation. All motion imparted to the work pieces results from the frictional contact between the work pieces and the endless carrier belt.

Referring specifically to the drawings, the numeral 10 indicates a central pedestal from each side of which extends a bed assembly 11 (Fig. 1). The ends of the bed assembly 11 are supported by legs 12. The bed assembly 11 is a box-like frame of rectangular cross-section hav-

2

ing a top bed plate 13 and a lower bed plate 14 joined by side structural pieces 15 (Fig. 2). The bed provides the support for an endless rubber-like belt 16 mounted to pass over pulleys at each end of the bed.

The pulley 17 is mounted on a shaft 18 (Fig. 4). The shaft 18 is positively secured to the gear reducer 20. The upper run of the belt 16 is supported by the upper bed plate 13 and the lower run of the belt 16 is supported by the lower bed plate 14.

Where the belt 16 passes beneath the cutter head, an opening is provided in the top bed plate 13 (Fig. 4). In the area of this cutout there is substituted for the upper bed plate 13 a plurality of freely rotatable rollers 25. The rollers 25 are each mounted on shafts 26 journaled in an end plate 27 on each side of the bed. The rollers 25 provide a substantially friction-free support for the belt 16 as it passes beneath the cutter head and its associated guide pieces in which area the work pieces are pressed tightly against the belt. The rollers 25 extend the full width of the belt, providing complete support for the belt in this area.

The belt 16 is described as being a rubber-like material. Various flexible, high strength materials having the desired high frictional surface characteristics may be used for this purpose. A rubber belt having embedded fabric or metallic reinforcement to prevent elongation and giving the belt sufficient tensile strength has been found to provide a satisfactory means of carrying the work pieces.

The main column 10 contains the cutter head and its related structure. The column 10 consists of a stationary base piece 40 on each side of the planer (Fig. 2). Above the base piece is the vertically adjustable head assembly 41 extending across the machine above the belt 16. The head assembly consists of a pair of side assemblies each of which has an arm 42 engaging a threaded shaft 43. The threaded shafts are each journaled for free rotation in a supporting block 44 and at their lower ends have a beveled gear 45. The beveled gears in turn engage mating beveled gears 46 secured on the lateral shaft 47. One end of the lateral shaft 47 projects exteriorly of the column 10 and is equipped with a hand wheel 48. The shaft also mounts a sprocket 49 engaged by the chain 50 and driven by the prime mover 51. Rotation of the threaded shafts 43 results in raising or lowering of the adjustable head 41.

On one side, the adjustable head 41 mounts a heavy duty prime mover 53 which, by means of belts 54 and the pulley 55, drives the cutter shaft 56. The cutter shaft 56 is journaled by means of the bearing blocks 57 at each end near the top of the adjustable head 41. The shaft 56, in turn, mounts the cutter head 58. The cutter head 58 is equipped with cutting blades 59 and is designed for rotation by the prime mover 53.

On the end of the shaft 56 remote from the pulley 55 an indexing assembly is provided. The indexing assembly consists of a head 62 having a notch 63 corresponding to each cutter blade 59. Above the head 62 is a depressible plunger 64 designed to engage the notches 63. The indexing assembly is designed to lock the cutter head 58 in position when the cutter blades 59 are sharpened.

The cutter head 58 is positioned above the upper run of the belt 16 and, by vertical adjustment of the adjustable head 41, may be raised or lowered with respect to the belt 16. Mounted transversely of the adjustable head 41, above the belt 16 and on each side of the cutter head 58, are guide assemblies. The following paragraphs will describe the guide assembly on the down stream side, that is, on the side of the cutter head from which the work is approaching.

The down stream guide assembly 70 is supported by

an L-shaped main supporting frame 71, extending transversely of the belt 16 and firmly secured to the adjustable head structure 41 on each end (Fig. 4). Below the supporting frame 71 and parallel to it is a pivot rod 72. The pivot rod extends transversely of the belt 16 and provides the hinge or pivot mounting common to all of the fingers 73.

A plurality of narrow finger members 73 are used. The purpose of this is to assure a positive downward pressure by the finger members on the work pieces as they approach the cutter head irrespective of whether the work pieces are wide or narrow. The fingers 73 are of such length that they extend from the rod 72 to the cutter head 58. The end of the fingers adjacent the cutter head are inclined at 69 so that the bottom tip of these fingers may reach practically to the point of contact between the work piece and the cutter head without interference with the cutter head.

Bearing on the upper surface of the fingers adjacent the cutter head and common to all the fingers, is a transverse bar 74. The bar 74, by means of an arm 75 on each side, is pivotally mounted to the rod 72. The bar 74 is supported entirely by the fingers 73. Any finger raised by the work pieces traveling on the belt must also lift the bar 74. This arrangement assures positive contact between the fingers and the work piece.

In addition, each individual finger is resiliently urged against the work piece by the spring 76 which surrounds the sliding stud 77. The upper end of the stud 77 is slidably received through an opening 78 in the transverse angle 79. The lower end of the stud 77 is pointed at 80 and is received in a suitable pocket in the finger 73. The tension on the spring 76 is adjusted by means of the nut 81 on the lower end of the stud. This arrangement assures positive downward pressure by each individual finger on any work piece passing to the cutter head. The maximum downward position of each finger 73 is controlled by the adjustment stud 82 on the down stream end of the supporting frame 71. The studs 82 are each locked in position by means of a nut 83.

The angle 79 is secured to the vertical leg of the supporting frame 71 by means of bolts 84.

On the down stream or opposite side of the cutter head 58 is a lintel 85. The lintel 85 extends the full width of the adjustable head assembly 41 and is firmly secured thereto for vertical movement with the adjustable head. The lintel provides, on each side of the belt 16, a vertical guideway 86 mounting a slide block 87 for vertical, sliding movement. The slide blocks 87 are each threadedly engaged by a vertical adjustment screw 88. The screws 88 pass through the top of the lintel 85 and above the lintel mount a sprocket 89. The sprockets 89 are joined by an endless chain 90. Thus, by gripping the bolt head 91 at the top of either of the screws 88, both screws will be rotated simultaneously by the coordinating action of the chain 90.

The bottoms of the slide blocks 87 secure a horizontal shoe 92 extending across the conveyor bed at least the full width of the belt 16. The shoe 92 is pointed at its upstream end 93 where it passes beneath the downstream portion of the cutter head 58. The bottom of the end 93 is slightly chamfered at 94 to prevent the work pieces, as they emerge from beneath the cutter head, from becoming jammed against the end of the shoe 92. The shoe is adjusted to the exact height of the work pieces as they emerge from beneath the cutter head. It serves the purpose of holding the ends of the boards down as they emerge, preventing them from curling up due to any internal stresses which may be released as a result of the planing operation.

Downstream of the shoe 92 is the pressure roller 96. The pressure roller 96 is designed to provide an additional means for holding down the end of the boards as they emerge from beneath the shoe 92 and to prevent the

boards, should they warp, from turning up as they emerge from under the shoe and thus being improperly planed by the cutter head 58 or lose their surface contact with the belt 16. The pressure roller 96 is mounted for vertical movement by means of a pair of sliding journal blocks 97 designed to vertically reciprocate in the vertical guideways 98 of the lintel 85. The sliding journal blocks 97 are mounted one on each end of the shaft 99 carrying the pressure roller 96.

The minimum spacing of the pressure roller 96 from the belt 16 is determined by the two adjustment screws 100, one on each end of the pressure roll and each threadedly engaging one of the journal blocks 97. The adjustment screws 100 are each free to slide through an opening in the top of the lintel 85 with the journal blocks moving against the resistance of the springs 101. The springs 101 surround the adjustment screws 100 and bear against the lintel 85 and the journal blocks 97.

The pressure roller is designed to be set slightly below the bottom face of the shoe 92. At this settling it will positively engage the work pieces as they emerge from beneath the shoe 92. The work pieces will raise the pressure roller 96 against the resistance of the springs 101 to positively press the work pieces against the belt 16 and to prevent their disengagement from its surface.

The surface of the pressure roller 96 is smooth. This is possible since it merely exerts downward pressure and does not propel the work pieces.

The vertical adjustments employed with the pressure roller 96, the shoe 92 and the fingers 73 are all adjustments for vertically positioning them relative to the cutter head 58. Since, however, these guide elements together with the cutter head are all mounted upon the adjustable head 41, they may all be raised or lowered as a group 35 with respect to the belt 16 without changing the positions of these individual elements with respect to each other.

Operation

40 In the operation of our machine, the movement of the work pieces through the planer is effected entirely by means of the belt 16. The work pieces are laid on the belt 16. By reason of the high frictional surface of this belt, these pieces are positively held and carried with the belt.

45 As they approach the cutter head, they strike one or more of the fingers 73, lifting them. This will always be the case, since the fingers 73 are at all times set to project slightly below the cutter head and the pieces as they approach the cutter head are thicker than when they leave it since a certain amount of the thickness is removed in the planing operation. The raising of the fingers 73 causes these fingers both to lift the bar 74 and to compress the springs 76. Depending upon the width of the work 50 piece, one or more of the fingers 73 will be raised. The raising of a single finger will effect a lifting of the bar 74. However, when more than one finger 73 is raised, the work piece will be subjected to the accumulative effect of resistance of the springs 76 operating upon each individual finger.

55 The fingers 73 positively press the work piece against the belt's surface assuring a firm, frictional grip between the belt and the work piece as the work piece passes in contact with the blades 59 of the cutter head 58. This frictional grip is sufficient to push or pull, as the case may be, the work piece past the cutter head despite the resistance of the cutter head as it removes a layer of the work piece.

60 The angle at which the fingers 73 are inclined with respect to the surface of the belt is important. This angle is approximately 8°. At this angle the fingers will not reject an unusually thick board since the retarding component of force generated by the fingers is substantially less than that required to cause the work piece to slip on the belt. This is true even though the

work piece is short. Thus, the fingers are set to what is sometimes termed the angle of no rejection. Because of this it becomes unnecessary for the operator to assist the machine's feeding operation with the hazard of injury attendant such practices.

This result is one which cannot be obtained in conventional roller feed constructions. Even though the work piece strikes the feed roller well below its centerline, the work piece is frequently rejected. This is inherent in roller feed arrangements and, thus, cannot be avoided so long as rollers are employed.

As the work piece emerges from beneath the cutter-head, it immediately engages the bottom of the shoe 92. The shoe 92, like the fingers 73, presses the work piece against the belt 16. This is important in wood working operations since many woods, when passed through a planer and a portion of one face removed, are subject to a redistribution of stress loads which may result in arching, bowing or curving in any one of several directions. The shoe 92, being locked by the screws 88 to the exact spacing for the particular thickness of the work piece after it emerges from beneath the cutter head 58, firmly holds the work piece against warpage. This assures its continued contact with the belt and prevents it from being miscut due to arching or warping as it passes beneath the cutter head.

The work piece, almost immediately after it emerges from beneath the shoe 92, is engaged by the pressure roller 96. The pressure roller 96, being set lower than the bottom of the shoe 92, must be forced upwardly against the resistance of the springs 101 by the passage of the work piece. The pressure exerted by the pressure roller 96 assures contact between the work piece and the belt as it passes through the planer.

Although in case of long pieces, the guide elements are not as essential as in the case of short work pieces, they do assure a better product. In the case of short work pieces, it is essential to assure positive contact with the belt as the work pieces move under the cutter head 58. This is accomplished by these particular guide elements since on the upstream side the end of the work piece is not released until it is almost at the point of cutting. At the same time, the work piece is engaged by the shoe 92 almost immediately after it emerges from beneath the cutter head.

However, more importantly, in so far as the planing of short lengths of wood are concerned, the use of the belt traveling the entire length of the bed, including beneath the cutter head, provides a positive carrier for the work pieces. Unlike conventional structures, the work pieces are at all times under the influence of the moving belt. The use of propelling rollers to move the work pieces through the planer necessitates the work piece at least having a length sufficient to more than bridge the gap between the propelling rollers on each side of the cutter head since it is only by contact with the propelling rollers that the work piece is caused to move. Further, the propelling rollers, by necessity, must have a substantial grip on the work piece since their contact is limited to a minute portion of the total area of the work piece.

By employing a belt, the entire bottom surface of the work piece serves as a gripping for propelling the work piece. This grip is maintained throughout the operation, even while the work piece is directly beneath the cutter head. Thus, work pieces as small as six inches in length may be successfully planed by this machine since it is only necessary that they have contact with the belt and with either the fingers 73 or the shoe 92 to prevent them pivoting upwardly under the rotative effect of the spinning cutter head 58. Never before has this result been accomplished.

The use of fingers 73 set at an angle of "no rejection" is also important in adapting the planer to the planing of short work pieces.

Furthermore, the pressures applied to the work pieces either by means of the fingers 73 or by the pressure roller 96 need be only a fraction of that required with the propelling rollers of conventional planer equipment. With the belt the entire bottom surface of the work piece is used to obtain traction. Further, the propelling rollers contacting the finished surface of the work must be smooth, thus producing limited traction. Such rollers must operate under elevated pressures to overcome the lack of traction incident to such surface characteristics. This reduction in pressure plus the ability to use a smooth surface on the belt, the guide elements and the pressure roller eliminates the imperfections which sometimes resulted from the use of such traction means as corrugated rollers. This machine may not only plane materials which were heretofore considered unsuited for planing but produces a superior product irrespective of the length of the material involved.

To positively control possible deflection of the belt under the operating pressures of the mechanism, it will be seen that one of the rollers 25 supporting the belt 16 is positioned directly beneath the cutter head 58. This arrangement assures positive support for the belt and the work piece at this point, resulting in accurate cutting of the material to the desired thickness. In the same way, it will be noted that one of the rollers 25 is placed directly beneath the pressure roller 96 to provide the same direct support in this area.

The use of the belt and pressure finger combination at the entrance to the planer contributes materially to the safety of the machine. If an operator's fingers are caught between the feed rollers, they normally cannot be withdrawn. Unless the machine is stopped, the rollers will draw the operator into the machine. In the case of the finger-belt combination, the operator may withdraw his hand before it is crushed and fed into the cutter head. The belt-finger combination does not acquire the same irresistible grip as that of a pair of rollers, particularly where one of the rollers is corrugated.

The simplicity of this invention provides a less expensive planer. Despite this simplicity, the planer is capable of producing results heretofore impossible and of producing these results consistently on a production basis.

While we have described a preferred embodiment of our invention, it will be recognized that various modifications may be made without departing from the principles of the invention. Each of these modifications is to be considered as included in the hereinafter appended claims unless these claims by their language expressly state otherwise.

We claim:

1. In a planer having a driven cutting head, a bed beneath said cutting head and projecting in both directions therefrom and means for guiding and moving a work piece beneath and in contact with said cutting head, said means comprising: a rubber-like belt having a surface characterized by a high coefficient of friction; said belt being mounted on and movable along said bed; means for driving said belt; a plurality of rollers mounted in said bed beneath said cutting head, said rollers being adapted to support said belt; one of said rollers being vertically aligned with centerline of said cutter head.

2. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of guide elements adjacent said cutting head; means mounting said guide elements for vertical pivotal movement above said belt and on the approach side of said cutting head with respect to the

movement of said belt; means biasing said guide elements toward said belt.

3. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of guide elements adjacent said cutting head; means mounting said guide elements for vertical pivotal movement above said belt and on the approach side of said cutting head with respect to the movement of said belt; means resiliently biasing said guide elements toward said belt; a shoe adjacent said cutting head and on the other side thereof from said guide elements; means mounting said shoe above said belt; said mounting means for said shoe including threaded members whereby said shoe may be vertically adjusted; means resiliently urging said shoe toward said belt.

4. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of belt supporting freely rotatable rollers mounted in said bed beneath said cutting head; guide elements above said belt adjacent to and on both sides of said cutting head; a pressure roller; means resiliently mounting said pressure roller for vertical movement above said belt and downstream of said guide elements with respect to the direction of movement of said belt.

5. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of guide elements adjacent said cutting head; means mounting said guide elements for vertical pivotal movement above said belt and on the approach side of said cutting head with respect to the movement of said belt; means biasing said guide elements toward said belt; a shoe adjacent said cutting head and on the other side thereof from said guide elements; means mounting said shoe above said belt; said mounting means for said shoe including a threaded member at each end thereof whereby said shoe may be vertically adjusted; a pressure roller; means resiliently mounting said pressure roller for vertical movement above said belt and downstream of said shoe with respect to the direction of movement of said belt.

6. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of elongated guide elements adjacent said cutting head, said guide elements extending longitudinally of said belt; means mounting said guide elements for vertical pivotal movement above said belt and on the approach side of said cutting head with respect to the movement of said belt; said guide elements being inclined toward said belt at an angle of approximately 8°; means biasing said guide elements

toward said belt; a shoe adjacent said cutting head and on the other side thereof from said guide elements; means mounting said shoe above said belt; said mounting means for said shoe including a threaded member at each end thereof whereby said shoe may be vertically adjusted; a pressure roller; means resiliently mounting said pressure roller for vertical movement above said belt and downstream of said shoe with respect to the direction of movement of said belt.

10 7. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt being mounted on said bed; a mounting pulley for said belt at each end of said bed; means for driving one of said pulleys; a plurality of guide elements adjacent said cutting head; means mounting said guide elements in side by side relationship laterally across said belt for vertical pivotal movement above said belt and on the approach side of said cutting head with respect to the movement of said belt; means individually biasing each of said guide elements toward said belt.

25 8. In a planer having a driven rotary cutting head, a bed beneath said cutting head, projecting in both directions therefrom and means for guiding and moving a work piece beneath and in contact with said cutting head, said means comprising: a rubber-like endless belt having a surface characterized by a high coefficient of friction; said belt mounted on said bed; a mounting pulley for said belt at each end of said bed; means for driving one of said pulleys; a plurality of elongated guide elements adjacent said cutting head, said guide elements extending longitudinally of said belt; means mounting said guide elements for vertical pivotal movement above said belt and on the approach side of said cutting head with respect to the movement of said belt; said guide elements being inclined toward said belt at an angle of approximately 8°; means biasing said guide elements toward said belt.

30 9. In combination with a planer having a driven rotary cutting head, a bed beneath said cutting head, projecting in both directions therefrom, a conveying means beneath said cutting head for moving said work piece 45 beneath and in contact with said cutting head; a plurality of guide elements adjacent said cutting head; means mounting said guide elements for vertical pivotal movement above said conveying means and on the approach side of said cutting head with respect to the movement of said conveying means; said guide elements being inclined toward said belt at an angle of approximately 8°.

35 10. In combination with a planer having a driven rotary cutting head, a bed beneath said cutting head, projecting in both directions therefrom, a conveying means beneath said cutting head for moving said work piece 50 beneath and in contact with said cutting head; a plurality of guide elements adjacent said cutting head; means mounting said guide elements for vertical pivotal movement above said conveying means and on the approach side of said cutting head with respect to the movement of said conveying means; said guide elements being inclined toward said belt at an angle of approximately 8°.

40 11. In combination with a planer having a driven rotary cutting head, a bed beneath said cutting head, projecting in both directions therefrom, a conveying means 55 beneath said cutting head for moving said work piece beneath and in contact with said cutting head; a plurality of guide elements adjacent said cutting head; means mounting said guide elements for vertical pivotal movement above said conveying means and on the approach side of said cutting head with respect to the movement of said conveying means; means resiliently biasing said guide elements toward said conveying means; a shoe adjacent said cutting head and on the other side thereof from said guide elements; means mounting said shoe above said conveying means; said mounting means for said shoe including members adapted to vertically adjust said shoe; means resiliently urging said shoe toward said conveying means; a pressure roller; means resiliently mounting said pressure roller for vertical movement above said belt and downstream of said shoe with respect to the direction of movement of said belt.

45 12. In combination with a planer having a driven rotary cutting head, a bed beneath said cutting head projecting in both directions therefrom, a conveying means

beneath said cutting head for moving said work piece beneath and in contact with said cutting head; a plurality of guide elements adjacent said cutting head; means mounting said guide elements for vertical pivotal movement above said conveying means and on the approach side of said cutting head with respect to the movement of said conveying means; said guide elements being inclined toward said belt at an angle of approximately 8°; means resiliently biasing said guide elements toward said conveying means; a shoe adjacent said cutting head and on the other side thereof from said guide elements; means mounting said shoe above said conveying means; said mounting means for said shoe including members adapted to vertically adjust said shoe; means resiliently urging said shoe toward said conveying means; a pres-

sure roller; means resiliently mounting said pressure roller for vertical movement above said belt and downstream of said shoe with respect to the direction of movement of said belt.
